[57] ABSTRACT

Ship's lifeboats with minimum of closely fitting parts made in symmetrical molds for left hand and right hand positions, each suitable for four different lifeboat types without change to molds. Major parts before final assembly comprising two sub-assembled sides with inner hull and hoisting bulkheads, two fairwater ends, one keel and sub-assembled seat-platform provision tanks. Simplified hoisting gear is provided for simultaneous release of two hooks from their respective hoisting links.

PLASTIC LIFEBOATS

This invention relates to new and useful improvements in lifeboats for use on ships, complying in all respects with the regulations of all of the principal maritime countries and, in particular, with those of the United States.

The following are considerations valuable to the understanding of this invention:

A. In the design of ocean-going vessels it is important to save on the top weight of the ship. Therefore, in the past, because of the weight factor, lifeboats made of aluminum became gradually preferable to those of steel. Steel or aluminum were used, for instance, in lifeboats described in prior patents Elling U.S. Pat. No. 2,233,254 of Feb. 25, 1941, Elling U.S. Pat. No. 2,328,437 of Aug. 31, 1943, and Elling U.S. Pat. No. 2,478,042 of Aug. 2, 1949, over which the present invention is an improvement in important aspects.

B. The advent, in recent years, of the use of plastic material in the manufacture of lifeboats has faced ship-builders and ship operators with a choice between aluminum lifeboats and lifeboats made of fiberglass-reinforced plastic hereinafter referred to as F-R P. The choice has been a difficult one because, although the cost of upkeep of F-R P lifeboats with foamed flotation tanks is low in comparison with lifeboats having metal air tanks, the weight of present-day F-R P lifeboats has turned out to be nearly as great as that of steel lifeboats. However, the weight of the F-R P lifeboats of this invention is equal to, or less than, the weight of presently built aluminum lifeboats. This and other advantages, disclosed hereinafter, will be understood and appreciated by those experienced in the art.

C. The term "fiberglass-reinforced plastic" (F-R P) is generally used in the trade for hand lay-up of fiberglass cloth, fiberglass woven-roving and fiberglass mat, after saturation with polyester resin.

D. Lifeboat construction has generally been a "custom-built" type of procedure. Parts are still installed or added one after the other with the boat in upright position and with scaffolds in constant use. Working with polyester resins on large, unwieldy products can be extremely unpleasant and often results in high cost and poor quality. Furthermore, the lay-up of F-R P material on vertical surfaces is difficult and should be avoided.

E. Government regulations specify the following types of lifeboats:

1. Oar propelled (only if under 599 cubic feet capacity).

2. Propeller driven, hand gear operated (only if 600 to 1,000 cubic feet capacity).

3. Diesel engine driven (any size to 36 feet in length).

4. Type 3 with radio cabin. In a lifeboat of this invention the designation of any of the above named types need not be made until after completion of all assembly except thwart platforms. Even a later change from one type to another, if required, is a minor operation. This is obviously of advantage to the lifeboat builder.

F. In the past, the pre-fabrication of parts was not popular because lifeboat sizes were not standardized. This has now been corrected. The lifeboat dimensions in way of the ship's davits and the arm dimensions of the davits have now been published in a standard lifeboat code by a technical committee, members of which

are appointed by several elements of the shipping and shipbuilding industries and by the Government.

Essential to this invention is the three-way split method of fabrication, along center line of lifeboat and hoisting bulkheads, allowing two sides, two fairwater ends and a keel to be pre-fabricated and stored to await final assembly. This method of fabrication is possible only because the parts, as described, cannot warp, sag or become otherwise misshapen.

The outer hull side, inner hull and gunwale brace panel, having been fabricated in individual molds, are interchangeable end for end and are clamped as a lifeboat side unit in a rotating rig with trunnions on pedestals at each end. Thus, the side unit may be turned in any position desired and all plastic lay-up and assembly work can be accomplished by operators standing on the shop floor. Rotating rigs can be used to great advantage in the lay-up operation of parts of this invention but they are not claimed as a novelty.

There are other advantages of the three-way split type of lifeboat assembly. For instance, it may be decided that the main plastic production occur at a plant which is located away from the final assembly plant. In the past it was customary that lifeboats be fabricated at one location. Today, due to my sub-assembled lifeboat side unit, which will not twist, warp or sag, it is feasible to have all primary lay-up of fiberglass-reinforced plastic done by a reputable company which is better able to keep its highly experienced operators and specialized machinery busy doing just such work in air conditioned shops.

Another feature of this invention relates to a hoisting gear arrangement with simultaneous hook release at each end as it is installed in a fiberglass-reinforced plastic lifeboat of this invention with three-way split feature of fabrication.

The method of installation of a hoisting gear in present-day plastic lifeboats is still very much as illustrated in FIG. 6 of Elling prior U.S. Pat. No. 2,478,042; that is, it is still mounted on a vertically positioned rectangular bar having a hook-body with a clevis-type back, a hook pin at its top through the clevis parts and a spoon-like plate support under the keel. Such an arrangement necessitates: (1) two universal joints at each end of the boat instead of one and (2) the positioning of the fore and aft release rod at lower thwart level instead of top thwart level which makes the operation of the hand lever over a swing of 180 degrees difficult. Therefore, it is a major object of this invention to provide means for a reliable, direct hull connection of the hoisting gear. The three-way split method of manufacture allows the simple one-piece construction of the outer hull half with the split hoisting bulkhead as an integral part, of which the required factor of safety of the hoisting gear connections can easily be calculated.

The inner hull side may be readily inserted in an outer hull side and may later, after completion of sub-assembly with all other lifeboat side parts, be joined together with the keel and with the similarly completed opposite side. The inner hull, all in one piece with three knuckles, comprises three straight, flat panels and a keel flange, terminating at their junction with the curved outer hull.

It is a further object of this invention to provide a new flexible gunwale bracing consisting of a flat longitudinal gunwale brace panel, which forms a triangular section with the upper part of the outer hull on each side

of the lifeboat. The upper part is flanged and bonded to the underside of the gunwale top and the lower edge butts against the inside reinforcement of the outer shell along the upper seat panel of the inner hull. A Coast Guard slamming test is required during which the lifeboat is swung against a ship's hull from a distance of ten feet. Because of the existence of a one-inch nosing projection near the gunwale top there will take place, during the test, some bending in the outer shell at the junction with the inner hull but no breakage will occur because the normally installed rigid braces from gunwale to seat have been eliminated and F-R P strips, tapered from the point of the three-part junction, are being used to gain flexibility.

Lifeboats are suspended from ships' davits with the hoisting points near their ends and, because of the great human load during lowering, there is need for longitudinal strength. The lifeboat of this invention is an ideal girder with the extreme top fibers in the gunwale sections and with the extreme bottom fibers in the keel section. It is only necessary to provide for strong braces and spreaders to keep above named bottom and top sections rigidly in place which is accomplished by inner hull, outer hull and transverse thwarts; All of which are forming a triangular box section. The inner hull, and the outer hull deep-bellied containers are again held in their position by poured-in-place foam with good adhering quality and with 30 to 50 PSI compressive and tensile strength.

The three-way split sub-assembly feature serves the purpose of divorcing the structurally unimportant fairwater ends from the hull structure and hoisting structure which, together, are a structural entity by themselves. The fairwater ends, completely filled with poured-in-place foam, are constructed with a thin F-R P shell without stem, sternpost or other stiffeners and thereby saving weight. Since the vertical part of the hoisting bulkhead is in exact line with the center of the ship's davit, the required chafing guard on the outer hull in way of the davit arms will cover the seam between fairwater end and the outer hull recess.

All lifeboats aboard ships are secured to each davit by over the gunwales, past the keel cables which are tightened, sometimes to excess, by turnbuckles. It is obvious that a lifeboat must be quite strong transversely to withstand the stress in way of these holding cables in adverse weather. The following parts of this invention will fill this need: A double-thick hoisting bulkhead, the ends of gunwale brace panel, an extended transverse cambered deck with doubling recess, a doubling recess in each outer hull-half with the edge area of the fairwater and a chafing guard doubling between keel and gunwale.

Another object of this invention is to provide, in a fiberglass-reinforced plastic lifeboat, for a strong outer hull without adding excessively to the thickness of the shell. However, the shell of this invention will still be capable of withstanding the drop of a fully loaded lifeboat into the water from a height of ten feet. On each side there are two sectionally half round grooves and one rounded offset, positioned longitudinally and at about equal distance from one another between gunwale and keel, extending about two-thirds the length of the lifeboat. The offset groove has been chosen to facilitate easy mold release which must be sideways because of the flanged gunwale top. The grabrails, in themselves not a part of this invention, have their supports inserted

in parts of these grooves. The combination of grooves in the outer hull and the presence of poured-in-place urethane foam over the area of the outer shell within the ends of the inner hull makes possible the elimination of all inside framing.

It is an object of this invention to provide means in a fiberglass-reinforced plastic lifeboat for a combination of transverse and lateral strength (the latter to withstand a 200 pound sandbag drop from a 6-foot height on the thwarts) with stability-producing storage facility near the keel, of a total of 11 pounds of water, milk and provisions, all in cans, for each passenger, under relatively thin thwarts which serve as fixed covers for deep bellied tanks.

15 A further object of this invention is the combination of a manual sea cock water inlet to increase stability in the lifeboat and the use of the same sea cock for draining excess water through a manually tended rubber hose. In the first instance, a water load right above the keel cannot splash sideways and will assure enough stability for the lifeboat to remain upright and in the second instance, by lifting the rubber hose end to the water level when sea cock is open, it will start draining until the outside level is reached.

20 25 Plastic lifeboats embodying this invention are shown in the accompanying drawings, of which:

FIG. 1 is a perspective view of the left side of a diesel driven lifeboat with parts cut off along the longitudinal center line. The fairwater ends of the lifeboat have 30 been omitted in this view for the purpose of clarity.

FIG. 2 is a fragmentary horizontal section on the line 1 — 1 of FIG. 1, showing the rabbet-like recess and demonstrating great transverse strength concentration in way of ship's davits.

35 FIG. 3 is an enlarged scale view on the line 2 — 2 of FIG. 9.

FIG. 4 is an enlarged scale view on the line 3 — 3 of FIG. 10. The gear unit base plate of FIG. 4 is identical in size to the gear unit base plate in FIG. 3.

40 FIG. 5 is a transverse vertical section on the line 4 — 4 of FIG. 1, except that the release rod is shown in FIG. 5 at center line. FIG. 5 also demonstrates schematically the sequence of foaming the inner hull area and the gunwale area without leaving air pockets, easily accomplished by rotating the lifeboat-half as described elsewhere.

Background of FIG. 5 is a view on the line 5 — 5 of FIG. 3.

50 FIG. 6 is an enlarged scale gunwale section of FIG. 5, showing securing clamp bolts which also serve as oarlock sockets and sockets for anti-exposure cover stanchions.

FIG. 7 is an enlarged scale keel section of FIG. 5 showing (1) the attachment of the boat hulls to the keel and (2) the recesses in the inner hull for two different fittings described elsewhere herein, the two fittings are secured to the inside of the outer hull but not necessarily at the same longitudinal position.

60 65 FIG. 8 is a transverse vertical section on the line 6 — 6 of FIG. 1. The thwart in way of the engine enclosure is shown slightly raised to show the possibility of installing a larger engine, if required. The complete engine unit with enclosure and brackets may be exchanged for a manually operated propelling gear unit without any change in the basic lifeboat structure. In a similar way and with similar brackets a prefabricated radio cabin may be installed in the location indicated in FIG. 10.

FIG. 9 is a plan view outline of lifeboat as in FIG. 5 but with its gear release rod along the center line.

FIG. 10 is a plan view of a lifeboat as in FIG. 8 but with its gear release rod off the center line and just clear of the engine enclosure or of the radio cabin or both.

FIG. 11 is a schematic arrangement of precision made parts lending themselves to easy assembly. All parts are interchangeable.

FIG. 12 is a bottom view of the outer hull halves showing the shell grooves and the hoisting bulkhead seam which is covered by the bolt washer plate.

FIG. 13 is an enlarged scale section on the line 7 — 7 of FIG. 12 with end view and plan view of a metal hand rail stanchion.

FIG. 14 is a perspective view of lifeboat parts from midship towards end, showing one inner hull, one gunwale brace panel and one fairwater end, all in proximate position to one another.

Referring to illustrated structure by reference numbers, the fiberglass-reinforced plastic (F-R P) outer hull shell 15 extends in a single piece on each side of the lifeboat between bulkhead center line butt aft 16 and bulkhead center line butt forward 17 and between inboard edge of gunwale top 18 and underside of keel 19. The curvature of the outer hull is conventional except that, at the hoisting points 20, the outer hull turns squarely towards the center line to abut at 16 and at 17 with the ends of the opposite identical lifeboat half, thus forming a transversely straight hoisting bulkhead 21 which has a transverse knuckle at 22.

An additional departure from the conventional outer hull are the grooves 23 and the rounded offset 24 positioned at about equal distance between gunwale and keel and having a length of about two-thirds the length of the lifeboat. The nosing projection 25 is a gunwale combination extending toward each end just short of imaginary transverse lines at hoisting points 20. The detail of grabrail stanchion 26 and the grabrail rod 27, which are not part of this invention, has been shown to demonstrate the suitability of grooves.

The fiberglass-reinforced plastic (F-R P) inner hull 29 extends in a single straight piece, in fore and aft direction on each side of the lifeboat, between the points of intersection 30 with the curved outer hull 15. The inner hull 29, in a zigzag form extends transversely from underside of keel 19 to its upper edge which butts against the outer hull reinforcement 46, at which point the inner hull is supported by longitudinal F-R P stringer 38 and thwart brace 31. Longitudinal hard-core laminated thwart support stringers 33 with backing stringers 34 are positioned just below upper and lower riser panel knuckles 32. The keel flange knuckle 32 of the inner hull fits snugly over the keel flange knuckle 32 of the outer hull.

The fiberglass-reinforced plastic (F-R P) gunwale brace panel 35 extends in a single piece on each side of the lifeboat longitudinally between end points 36 which are approximately on an imaginary transverse line through hoisting points 20, at each end. The upper part is rounded at 37 and flanged under gunwale top 18 and the lower edge is locked in the corner formed by the inner hull 29 and outer hull reinforcement strip 46. Full enclosure is assured by F-R P bonding strip 28. Additional strength is provided by a combination of metal sleeve nuts 39 and hollow threaded bolts 40 which have a slanted head with tie rope eyes 41. The hollow bolts

are suitable for oarlock sockets and for cover stanchion sockets.

The fiberglass-reinforced plastic (F-R P) fairwater end 42 with fairwater deck 42A at each end of the lifeboat is molded to a precise fit in the rabbet-like recess 43 which is formed along the perimeter of the hoisting bulkhead in the deck extension 18A and in the side shells of outer hull 15. After assembly, inside space is filled with foam 47 through vent and fill holes 48. The lower part of hoisting bulkhead 21 below knuckle 22 is vertical and in line with hoisting points 20 and with the center of the davit arm rest 44. The multi-purpose F-R P doubling strip 45 is added to the outside of the outer hull and the fairwater end, to cover the recess seam and to protect the outer hull against chafing in way of the davit arm rest 44.

The secondary lay-up of fiberglass-reinforced plastic (F-R P) 46 is only for those inside areas of the outer hull halves 15 which are not covered by inner hull 29 or by gunwale brace panel 35. The F-R P lay-up 46 is also used for the total inside areas of each hoisting bulkhead 21 and for strip 46 to cover the recess seam and to protect the outer hull against chafing in way of the davit arm rest 44.

The filling of hollow spaces between outer hulls 15 and inner hulls 29 and between outer hulls 15 and gunwale brace panels 35 with poured-in-place urethane foam 47 requires a set-up and procedure suitable for the avoidance of air pockets when pouring foam and for allowing operators to remain on the shop floor during such operation. This is made possible by a three-way split lifeboat assembly method made obvious by the following described procedure. A lifeboat-half thus far described is clamped in a rotating rig with trunnions on pedestals at each end and by simple hand rotating of the lifeboat-half unit. The machine mixed foam liquid is blown by a nozzle through fill and vent holes 48 with the rig turned so that foam part 47A is at the lowest position, followed by 47B; the extreme ends may then be filled by raising one end after the other, always checking the vent and fill holes 48. After a short wait, the rig is turned so that 47D is at the lowest position, followed by 47E and then, after another short wait, turned back to 47C and finally to 47F until all vent and fill holes show positive escape of foam. In a similar way the space between outer hull 15 and gunwale brace panel 35 is filled with foam. The vent and fill holes 48 are plugged with F-R P.

The fiberglass-reinforced plastic (F-R P) keel 49 extends in a single piece slightly beyond the hoisting bulkheads at each end of the boat where the straight underside of the keel 50 serves as lifeboat rest in ships davit arms. The keel arms 51 are reaching up and are butting against the center line seam of the bulkhead halves 21 and are secured by bolted angles 52.

The heads of bolts 53 are permanently attached to bolt-washer plate 54. The thread of bolts 55 is projecting inside of lifeboat for securing angles 52 and hoisting unit base plate 56. The latter has attached hook side plates 57, painter eye clip 58 and hook lock cup bearing 59. Movable parts of the lifeboat hoist gear and its manual simultaneous release gear at each end are: Hook 60, hook pin 61, hook lock cup 64, hook lock extension 65, universal joint 66, joint support and cover guard 67, release rod 68 and attached hand release lever 69. Parts 64, 65 and 66 are permanently attached to one another. The distance 62 between hoisting link

20 engaged by hook 60 and hoisting hook pin 61 is kept to a minimum for the purpose of reducing, during the lowering operation, the stress against the hook shank 63 making it easier to turn the hook-lock cup 64 which has an open rim on one side. There is also, because of said reduced friction in the cup, less effort required on the release lever 69 and, for the same reason, the release rod 68 can be reduced in size. The possibility of a sluggish hook release, which might occur if the life-boat is swinging longitudinally, is prevented by a longer hook pin 61, projecting on each side so that the davit hoist link 20 will bear on the projections of hook pin 61 and thereby force hook 60 to swing open.

The double width seat platforms or upper thwarts 70 and 71 and the lower thwarts 72 of hard-core laminated material are secured to longitudinal supports 33. The upper thwarts 70 serve as air-tight covers for the fiber-glass-reinforced plastic (F-R P) provision containers 73 and for the fuel container 74. The thwart 71 is not attached to the engine enclosure 76 but it is increased in thickness and may have an offset 71A, if required, to suit height of engine 75 and engine enclosure 76.

The engine shaft sleeve 78 is secured to side of keel arm 51. Double thick upper end-thwarts 79 are bracketed to keel arm angles 52. The engine 75 and engine enclosure 76 have permanently attached brackets 77 connected to and supported by longitudinal stringers 33. The radio cabin 81 is bracketed in a similar way to stringers 33.

Each inner hull-half 29 is provided with a recess 80 having a bottom 80A to accommodate a drain fitting 82 with a rubber ball 83 in the outer hull-half 15 or, in the recess 80 of the identical opposite inner hull-half to accommodate a manual bilge water control sea cock 84 with a short rubber hose 85.

I claim:

1. In a lifeboat of fiberglass-reinforced plastic, an outer hull-half in one piece on each side symmetrical and identical with opposite outer hull-half, each fabricated from a single symmetrical mold thus allowing the turning of one of two outer hull-halves end for end for using one on left side and one on right side, each of said hull-halves curving inboard towards the ends and at hoisting points squarely turning inboard to a meeting with the opposite hull-half at center thus forming at each end a flat but knuckled hoisting bulkhead with the knuckle at about half its height, a longitudinally straight knuckled inner hull-half in one piece on each side and each fabricated from a single symmetrical mold thus allowing the turning of one of two inner hull-halves end for end for installing one in left outer hull-half side and one in right outer hull-half side, each comprising a longitudinal bottom keel flange, a lower riser panel, a middle riser panel, and a top seat panel, all extending parallel to the center line and terminating where each panel intersects with the curved outer hull, said seat panel and ends of riser panels bonded to inside of outer hull by F-R P strips, a longitudinal laminated hard-core thwart support stringer with backing stringer bonded to inner hull below upper knuckle of each riser panel for support of upper and lower thwarts, a gunwale brace panel in one piece in each of said outer hull-halves and each fabricated from a single symmetrical mold thus allowing the turning of one of two gunwale brace panels end for end for installing one in left outer hull-half side and one in right outer hull-half side,

extending between the gunwale ends and following its curve in inclined position with its lower edge at connection of seat panel to outer hull and with an outwardly flanged top bonded to underside of outer hull top flange or gunwale top, a double width flat F-R P keel interchangeable end for end positioned vertically in a single piece between bulkheads at each end with its lower part bonded between inner hull and outer hull flanges, an arm of the keel at each end reaching up to butt against the center line seam of the hoisting bulkheads which are part of the outer hull-halves and attached by bolted angles on each side, underside of keel at each end below the bulkheads made suitable to serve as keel rests on davit arms when in stowed position, a symmetrical saucer-like shaped fairwater boat end attached to each end of the outer hull by bonding in a rabbet-like recess along the perimeter of the said hoisting bulkheads, three or more laminated hard-core double width seat platforms or thwarts positioned athwartship about two and one half feet apart and their ends secured to said upper thwart support stringers forming the top of deep-bellied F-R P provision containers, one hoisting and simultaneous release gear unit with interchangeable unit base plate straddling the said bulkhead seam of the diagonally positioned upper part of said hoisting gear bulkhead on each end of the lifeboat, hollow space between said outer hull-halves and said inner hull-halves and between fairwaters and hoisting bulkheads and between said gunwale brace panels and outer hull-halves filled with light poured-in-place urethane foam.

2. In a lifeboat of fiberglass-reinforced plastic as in claim 1, having said hoisting bulkhead vertical in the lower part and diagonally inclined away from midship in the upper part with the top flanging towards amidship to form a cambered deck extension which is in a fair line with the gunwale top on each side and with the deck of said fairwater, a rabbet-like recess along the perimeter of the hoisting bulkhead-halves at sides and top to accommodate the open rim area of the fairwater boat ends, a bolt washer plate straddling the butt seam of the bulkhead-halves on the far side from midship with welded bolt heads whose threads are projecting inside of the lifeboat.

3. In a lifeboat of fiberglass-reinforced plastic as in claim 1, said symmetrical saucer-like shaped fairwater at each end of the lifeboat having a curved pointed end two curved sides and a cambered deck and its open rim area being attached by bonding to the outer hull in a rabbet-like recess along perimeter of said hoisting bulkheads, said fairwater having a slot opening at its lower pointed end allowing insertion of keel for forming davit rest, an anti-chafing doubling strip of F-R P outside of said outer hull and of fairwater rim centered in line with lower part of hoisting bulkhead and covering the recess seam on each side of the lifeboat from keel to gunwale.

4. In a lifeboat of fiberglass-reinforced plastic as in claim 1, said symmetrical outer hull-half having a bottom keel flange and a gunwale top flange with the latter in combination with a half-round outboard nosing projection extending longitudinally just short of hoisting bulkheads at each end, two longitudinal half-round grooves and one offset groove with rounded corners for hull stiffening and for secure and simple installation of

hand grabrails in each outer hull-half positioned at equal distance between gunwale and keel and having a length of about two-thirds the distance between life-boat ends, said offset groove to facilitate necessary sideways mold release, a recess in said lower riser panel of inner hull adjacent to said keel flanges on each side and of a size to suit the installation of a standard one inch sea cock flange or of a drain fitting flange with the recess bottom bonded to the inside of said outer hull-half.

5. In a lifeboat of fiberglass-reinforced plastic as in claim 1, said inner hull-half seat panel positioned about 10 inches below gunwale top having its outer edge terminating where it intersects with curved outer hull, said gunwale brace panel forming a triangular hollow section with gunwale top flange and upper part of outer hull, bonded together and filled with light poured-in-place urethane foam, a number of self-draining metal socket tubes positioned nearly vertical through said triangular section having flanged heads and inside thread at lower ends engaging thread matching hollow bolts with slanted heads firmly holding gunwale top and gunwale brace panel together thereby adding additional strength and for use as sockets for oarlocks and cover stanchions.

6. In a lifeboat of fiberglass-reinforced plastic as in claim 1, said top seat panel of inner hull-half positioned about ten inches below gunwale top at midship and terminating where it meets with the curved outer hull, longitudinal laminated hard core thwart support stringer and backing stringer bonded to said inner hull below upper knuckle of each riser panel one for upper thwarts and one for lower thwarts, three or more laminated hard core double width upper seat platforms or thwarts positioned athwartship about two and a half feet apart and their ends secured to said upper thwart support stringers and forming the top of airtight deep-bellied F-R P provision containers which are formed so that they have contact with said keel and with said support stringer for lower thwarts providing girder bracing between extreme top fibers in the gunwale sections and

extreme bottom fibers in the keel section.

7. In a lifeboat of fiberglass-reinforced plastic as in claim 1, said knuckled hoisting bulkhead whose upper part above said knuckle leaning away from midship, a hoisting gear unit base plate positioned above said bulkhead knuckle, a flat swinging hoisting hook engaged by a hook pin in two side bracket plates which are attached to said gear unit base plate, a hook lock extension which is part of a single universal joint at each end in the center of the lifeboat, a hook-lock cup bearing attached by bracket to said gear unit base plate and engaging a hook lock cup which is attached to upper end of said hook lock extension and has a cut-away rim on one side, a rotating horizontal release rod extending at upper seat level along the center line of the lifeboat between said universal joints and having a single hand operated release lever attached for simultaneous release of both hooks.
- 15 8. In a lifeboat of fiberglass-reinforced plastic as in claim 7, wherein: said rotating horizontal release rod extending at upper seat level and about fourteen inches off center line of the lifeboat between two universal joints, each bracketed to reinforced end thwarts and said horizontal release rod having a single hand operated lever attached for simultaneous release of both hooks, at each end a swinging hoisting hook which is flat in its upper part with hook bight in vertical line with lower part of said hoisting bulkheads and engaged by a hook pin, two hook side bracket plates which are attached to said gear unit base plate, a hook locking tail or shank pointing down to one side in direction toward said hook lock extension which is part of the single universal joint at each end of the lifeboat, a hook lock bearing attached by bracket to said gear unit base plate and engaging hook lock cup being attached to said hook lock extension and having a cut-away rim on one side and opposite rim to have its center when in locked position directly in line with center of upper part of hook.
